ENGRAVING MECHANISM

Application filed January 21, 1926. Serial No. 82,661.

My invention relates to engraving mechanism particularly the type employed for cutting the design in tire molds and the principal object of my invention is to provide a new and improved mechanism of this type. In the drawings accompanying this specification and forming a part of this application I have shown, for purposes of illustration one form which my invention may assume. In these drawings:

Figure 1 is a front elevation of this illustrative embodiment of my invention,

Figure 2 is a view taken from the side in Figure 1,

Figure 3 is a plan view omitting the cutter heads and the supports therefor to more clearly show the work supports and the actuating and control and spacing mechanisms,

Figure 4 is a section through the pattern mechanism taken on the line 4—4 of Figure 3,

Figure 5 is a section at right angles to that of Figure 4 taken on the line 5—5 of Figure 4,

Figure 6 is a plan view of the pattern plate,

Figure 7 is a fragmentary section taken on the line 7—7 of Figure 3,

Figure 8 is a detail of the spacing mechanism looking to the rear with the mechanism in front of the spacing mechanism removed to more clearly show the spacing mechanism,

Figure 9 is a side elevation of the cutter head, while

Figure 10 is a section on the line 10—10 of Figure 9.

The engraving mechanism herein shown comprises a plurality of units A arranged side by side preferably upon a common sub-base B.

Each of the units A comprises a base section 21 elongated transversely of the axis connecting the units A and provided at its forward end with a table 22 surmounted by an intermediate member 140 rotatably mounted on the table 22 by means of an annular boss 141 provided on the lower face of the intermediate member 140 and extending into and riding in an annular groove 25 in the upper face of the table 22, while the intermediate member 140 is in turn surmounted by a work support 23 rotatably mounted on the

intermediate member 140 by means of an annular boss 24 provided on the lower face of the work support 23 and extending into and riding in an annular groove 142 in the upper face of the intermediate member 140. 55

At the rear each base section 21 is provided with a radially extending guideway 26 on which is reciprocably mounted a bracket 27 reciprocable on the base section 21 by means of a screw 28 rotatable in the base section 21 and engaging a nut element (not shown) integral with the bracket 27 to thus advance and retract the bracket 27 upon rotation of the screw 28; while positioned on the inner face of the bracket 27 is a vertical guideway 30 on which is mounted a support 31 reciprocable along the guideway 30 by means of a screw 32 rotatably mounted in the bracket 27 and engaging a nut element (not shown) integral with the support 31 to thus raise and lower 65 the support 31 along the guideway 30 upon rotation of the screw 32.

Extending inwardly from the base 34 of the support 31 are a pair of spaced plates 35 and 36 having secured thereto by means of machine screws 37 a pair of cleats 38 carrying trunnions 39 effective to pivotally support from and between the plates 35 and 36 a cutter head 40 comprising a tubular casing 41 provided with recesses 42 for receiving the trunnions 39 and carrying reciprocably within its bore a sleeve 43 which in turn acts as a bearing for a shaft 44 carrying at its lower end a cutter element 45 rotated from an electric motor 46 by means of a belt 47 transmitting the rotation of the motor 46 from the motor pulley 48 to a pulley 49 carried by a shaft 50 carrying at its inner end a bevel gear 51 meshing with a bevel gear 52 splined to the reduced extension 53 of the shaft 44 the reduced extension 53 of the shaft 44 being guided in a bearing 54 carried by a bracket 55 extending from the upper end of the tubular casing 41 and also comprising a sleeve 56 effective to support the shaft 50 carrying the pulley 49 and the bevel gear 51. 95

In a design wherein each element extends to the center line of the mold it would be possible to maintain the cutter 45 advanced at all times and to make the entire cut by mill- 100

ing with the peripheral face of the cutter 45, but with a design in which every element does not extend to the center line of the mold it is essential that the initial cut in each such element be made by the cutter 45 by a drilling action as the cutter 45 moves to its advanced position from a previously retracted position. As a matter of fact it is also convenient to utilize this same action in cutting a design where every element does extend to the center line of the mold.

In order to permit this advance of the cutter 45 I mount the sleeve 43 for reciprocation within the tubular casing 41 and elongate the spline on the extension 53 of the shaft 44 so that the extension 53 may slide within the bevel gear 52 and the entire shaft 44 and sleeve 43 may slide within the tubular casing 41, and, in addition, I provide means for accomplishing this reciprocation of the shaft 44 and the sleeve 43, this means being herein shown as an arm 57 pivotally mounted at 58 on a bracket 59 carried by the upper end of the tubular casing 41, restrained in its movement upwardly by means of a set screw 60 adjustably mounted in a lug 61 carried by a lever 62 extending from the bracket 59, movable upwardly against the set screw 60 by means of an air cylinder 63 extending between the arm 57 and a bracket 64 extending from the lower end of the tubular casing 41, biased downwardly away from the set screw 60 by means of a tension spring 189 also extending between the arm 57 and the bracket 64, and transmitting this movement to the sleeve 43 by means of an integral sector 65 extending through an aperture 66 in the tubular casing 41 into mesh with a rack 67 carried by the adjacent surface of the sleeve 43.

Oscillation of the cutter head 40 on the trunnions 39, and advancement of the tool 45 laterally into the work, is imparted to the cutter head 40 by means of a sector 68 secured to the upper end of the casing 41 adjacent the junction of the bracket 55 and operated by a gear 69 carried by a shaft 70 mounted in a bearing 71 in the plate 35 and is in turn operated by means of a gear 143 mounted upon a shaft 144 rotatable in a bearing 145 also formed in the plate 35.

In order to maintain, during the swinging of the cutter head 40, the driving connection between the motor pulley 48 and the driven pulley 49 carried by the shaft 50 mounted in the bracket 55 on the cutter head 40, the motor 46 is mounted upon an arm 78 pivoted to a bracket 79 rising from the support 31 and the motor 46 is connected to the cutter head 40 by means of a strut 80 pivotally connected to the motor 46 concentrically with the shaft 81 of the motor pulley 48 and to the cutter head 40 concentrically with the shaft 50 of the pulley 49 and accordingly effective to swing the motor supporting arm 78 about its pivot on the bracket 79 to main-

tain the centers of the motor pulley 48 and driven pulley 49 at all times a fixed and constant distance apart, and to thus preserve the operating connection between the motor 46 and the cutter head 40 regardless of the oscillation of the cutter head 40.

The screws 28 are all operated in unison from a hand wheel 146 mounted on a shaft 147 supported on the rear ends of the several base sections 21, connected to the screws 28 by a succession of bevel gears 148 each meshing with a cooperating bevel gear 149 on one of the screws 28, and therefore effective to advance and retract all of the brackets 27 in unison upon operation of the single hand wheel 146; the screws 32 are all operated in unison from a hand wheel 150 mounted on a shaft 151 supported by the brackets 27 of the several units A, connected to the screws 32 by a succession of worms 152 each meshing with a cooperating worm gear 153 on one of the screws 32, and therefore effective to raise and lower all of the supports 31 in unison upon operation of the single hand wheel 150; the air cylinders 63 are all operated in unison by connection to a single supply line controlled by a single valve (not shown); the cutter heads 40 are all coordinated to oscillate in unison by means of connections 188 extending between the shafts 144 of the various units A and are operated in unison by means of a single actuating lever 154 secured to the shaft 144 of the left hand unit A, and, if we may assume for the present that each work support 23 rotates as a unit with the corresponding intermediate member 140, the intermediate members 140 and work supports 23 are coordinated to operate in unison by means of a reciprocating member 155 connected to arms 156 extending rearwardly from the intermediate members 140, and are operated in unison by means of a lever 157 pivoted at 158 to a projection 159 extending from a pedestal 99 rising from the base 21 of the left hand unit A and also carrying a slide 101 reciprocable in guideways 100 formed in the pedestal 99, connected to the lever 157 by means of a link 160, and connected by means of a lever 161 to the point of pivotal connection of the reciprocating member 155 and the arm 156 of the left hand unit A.

From the above description it will be obvious to those skilled in the art that operation of the actuating lever 154 will rotate the shafts 144 of the various units A to oscillate the cutter heads 40 of all of the units A in unison, and, still assuming that each work support 23 operates as a unit with the corresponding intermediate member 140, that operation of the actuating lever 157 will act through the reciprocating member 155 to oscillate in unison all of the intermediate members 140 and work supports 23.

Under these circumstances it is of course

obvious that exactly the same design will be cut by each unit A.

It will of course be obvious to those skilled in the art that under these circumstances it is entirely possible to cut the desired design by manual coordination of the oscillations of the work supports 23 and cutter heads 40, and also that under certain circumstances it may be desirable to coordinate these oscillations manually. Under many circumstances, however, a mechanical coordination is preferable and I therefore provide such coordination herein by coordinating the actuation which may be imparted to the cutter heads 40 and work supports 23 by the actuating levers 154 and 157, this coordination being effected herein by providing on the shaft 70 of the left hand unit A a second gear 162 meshing with a segment 163 carried by a lever 164 pivoted at 165 to the supporting plate 35 and connected by means of a link 166 to a slide 109 reciprocably supported in guideways 108 in the pedestal 99 and carrying a pin 118 extending downwardly into the cavity 119 in a pattern plate 120 secured to the slide 101 by means of set screws 122 and having its cavity 119 of that contour which in coordination with the pin 118 will restrict the movements of the actuating levers 154 and 157, and of the work supports 23 and cutter heads 40, to within the limits of the design desired to be cut by each of the cutting units A.

It will be understood that with such an arrangement the cutting devices are operated until the cutting tools 45 have cut out the entire substance within the limits of the desired design, that the control herein shown is not automatic in the sense that it itself causes the oscillations of the work supports 23 and cutter heads 40 necessary to cut the desired design, but on the contrary that the control herein shown merely limits the cutting to the limits of the desired design and leaves the oscillation of the work supports 23 and cutter heads 40 to be effected by the operator within these limits by operation of the actuating levers 154 and 157.

In the above discussion of the operation of the device each work support 23 has been assumed to operate as a unit with the corresponding intermediate member 140 and were each of the cutting units A to be called upon to cut the design but a single time such a construction would be entirely satisfactory. In engraving a tire mold, however, it is necessary to repeat the design many times about the periphery of the mold and accordingly a machine for that use must be so constructed that each work support 23 does move exactly with the corresponding intermediate member 140 during the cutting of any one design to accurately transmit to each work support 23 the actuations of the pattern plate carrying slide 101, yet is movable relative to the corresponding intermediate member 140 to space

the work supports 23 between successive repetitions of the design.

In the embodiment of my invention herein shown I accomplish this result by providing on the rear side of each intermediate member 140 a gear sector 167 arranged to mesh with a single elongated rack 168 mounted for reciprocation upon the base sections 21 of the various units A, by providing about the periphery of each work support 23 a worm gear 169 arranged to mesh with worms 170 carried by a single elongated shaft 171 rotatably mounted upon the base sections 21 of the various units A, by securing the shaft 171 and rack 168 against relative reciprocatory movement whereby, in the absence of rotation of the shaft 171, the rack 168 and shaft 171 force the intermediate members 140 and work supports 23 to rotate in unison and, upon rotation of the shaft 171, the worms 170 are effective to advance the work supports 23 relative to the intermediate members 140 to secure the desired spacing of the work supports 23 into position for repetition of the design.

In the embodiment of my invention herein shown I secure this coordination between the rack 168 and the shaft 171 by securing both to a base 172 reciprocable in a pedestal 173 carried by the base section 21 of the left hand unit A, the shaft 171 being rotatably and non-reciprocably mounted in a bearing 174 carried by the base 172 and the rack 168 being secured directly to the base 172 by a pair of machine screws 175, and I provide for the desired rotation of the shaft 171 by means of a dividing head consisting of an arm 132 pivoted upon an extension 176 of the base 172, provided with a handle 133 comprising a stop pin 134 arranged to seat within an aperture 135 in the extension 176 to hold the arm 132 against rotation, and provided also with a gear 136 formed integral with the arm 132 and connected through an intermediate gear 137 to a gear 138 carried by the shaft 171, the intermediate gear 137 being employed to permit the use of a wide variety of change gears to provide a wide range in the angle through which the work supports 23 are spaced to thus provide a wide variation in the number of times the design may be repeated in a single mold.

To those skilled in the art it will be obvious that under normal conditions the shaft 171 is locked against rotation by the presence of the pin 134 in the recess 135 and that under this condition the worms 170 become in effect a rack meshing with the worm wheels 169 and effective, in cooperation with the rack 168 meshing with the sectors 167, to force each work support 23 to rotate in unison with the corresponding intermediate member 140, that this result is achieved without interfering with the oscillation of the work supports 23 by the actuating lever 157 by interconnecting the rack 168 and shaft 171

through the base 172 itself slidably mounted, and that upon rotation of the shaft 171 by the means of the dividing head lever 132 the worms 170, acting from the base 172 as fixed by the engagement of the racks 168 with the intermediate members 140, act through the worm gears 169 to rotate each work support 23 relative to the corresponding intermediate member 140 to thus space each work support 23 for the repetition of the design and by an amount determined by the change gears 137 and 138 and therefore widely variable to widely vary the number of times the design is repeated in the mold.

In the above discussion of the device it has been assumed that the cutter 45 retained the same reciprocating position throughout the entire cutting operation. In many cases the design is laid out on an arc and it is entirely possible for the cutter to act in this manner. In other cases, however, and particularly in engraving designs extending down over the side wall of the tire, it becomes desirable to automatically vary the reciprocating position of the cutter 45 to avoid the inconvenience and expense resulting in following the practice now general in the art of dividing each such design into two or more parts each of which may be engraved without change in reciprocating position of the cutter.

In the embodiment of my invention herein shown I disclose means for automatically accomplishing this change in reciprocating movement of the cutter 45 by providing for variation in position of the set screw 60 by pivoting the carrying arm 62 to the supporting bracket 59 at 177, prolongating this supporting arm 62 beyond the pivot point 177, and providing on this prolongation 178 a lower pin 179 arranged to ride in the groove 180 of an arcuate cam 181 fixed to the side plate 36 and effective through the pin 179 and lever 62 to vary the position of the stop screw 60, and therefore of the arm 57 and sleeve 43 and cutter 45, to at all times maintain the cutter 45 at that reciprocating position corresponding to and determined by the contour of the cam groove 180 at that point corresponding to the then oscillatory position of the cutter head 40 upon the supporting plates 35 and 36.

From the above description it will be obvious to those skilled in the art that by properly forming the cam groove 180 I may provide any desired reciprocating movement of the cutter 45 as the cutter head 40 oscillates, to thus provide any desired cross-sectional contour for the base of the cut, and particularly that I may form the side wall design simultaneously with the operation of forming the tread design, and also that I may form a tread design in which the base of the cut is other than arcuate.

It will of course be obvious that I may reciprocate all of the cutters 45 in unison by

providing like cams 181 on all of the cutter heads 40.

And it will also be obvious that I may operate as many units as desired and not merely two as shown herein.

On the other hand, those skilled in the art will realize that the molds to be engraved vary slightly in thickness even when supposed to be identical, and that a certain amount of adjustment is required in each unit A to care for this variation. Inasmuch as the supports 31 are all raised and lowered in unison I find it convenient to provide this individual adjustment in the manner herein shown, by forming each work support 23 in the form of a lower section 182 carrying the annular boss 24 and the worm gear 169, and an upper section 183 directly supporting the work and screw-threaded to the lower section 182 to effect the desired adjustment by rotation relative to the lower section 182 and then be locked in adjusted position by suitable securing means (not shown).

I may also form in the lower section 182 an annular T-slot 184 arranged to receive the heads 185 of bolts 186 freely slideable for spacing until tightened by rotation of the handled nuts 187 to lock the work support 23 to the intermediate member 140 independently of the rack 168 and shaft 171.

From the above description it will be obvious to those skilled in the art that I have provided engraving mechanism of the type suitable for engraving tire molds formed to engrave in a single operation a design of a contour other than arcuate, and operable to adjust all of the brackets 27 in unison and all of the supports 31 in unison, to adjust the work tables 23 individually, to actuate all of the work tables 23 in unison and all of the cutter heads 40 in unison, and to reciprocate all of the cutters 45 in unison, to thus engrave a plurality of molds in unison by a single operator from a single control and operating apparatus. Under these circumstances it will be obvious to those skilled in the art that I have provided engraving mechanism possessing advantages not possessed by any engraving mechanism heretofore known.

At the same time it will be obvious to those skilled in the art that the particular embodiment of my invention herein shown and described may be variously changed and modified without sacrificing the advantages of my invention or departing from the scope thereof. It will therefore be understood that the disclosure herein is illustrative only and that my invention is not limited thereto.

I claim:

1. Engraving means comprising a plurality of units each comprising a rotary work support, an intermediate member mounted concentrically with said work support, a cutter, and means supporting said cutter and said work support for rotation of said work

support and for additional relative movement of said cutter and said work support effective to produce, with such rotation of said work support, relative movement of said cutter and said work support two-dimensional along the surface being engraved; common actuating means for effecting such movement in all of said units in unison, comprising reciprocating means engaging said intermediate members for effecting such work support rotation in all said units in unison; and common spacing means interposed between each of said intermediate members and the corresponding work support effective to produce periodically, in all of said units in unison, additional such rotation of said work supports, to thus periodically space said work supports in unison for the presentation of successive areas for engraving.

2. Engraving means comprising a plurality of units each comprising a rotary work support, a worm gear rotating with said rotary work support, an intermediate member mounted concentrically with said work support, a cutter, and means supporting said cutter and said work support for rotation of said work support and for additional relative movement of said cutter and said work support effective to produce, with such rotation of said work support, relative movement of said cutter and said work support two-dimensional along the surface being engraved; common actuating means for effecting such movement in all of said units in unison, comprising reciprocating means engaging said intermediate members for effecting such work support rotation in all said units in unison, and common spacing means, comprising in each unit a worm mounted to move with said intermediate member and meshing with the corresponding worm gear, effective to produce periodically, in all of said units in unison, additional such rotation of said work supports, to thus periodically space said work supports in unison for the presentation of successive areas for engraving.

3. Engraving mechanism comprising a pair of units disposed horizontally spaced from each other and alined and each comprising a work support movable in one dimension along the surface being engraved and a cutter mechanism movable in another dimension along the surface being engraved, to thus provide relative movement between said cutter and said work support two-dimensional along the surface being engraved; a first common actuating means for effecting such work support movement in all of said units in unison; and a second common actuating means for effecting such cutter mechanism movement in all of said units in unison.

4. Engraving mechanism comprising a pair of units disposed horizontally spaced from each other and alined and each comprising a work support movable in one dimension

along the surface being engraved and a cutter mechanism movable in another dimension along the surface being engraved, to thus provide relative movement between said cutter and said work support two-dimensional along the surface being engraved; a first common actuating means for effecting such work support movement in all of said units in unison, comprising a coordinating means connected to each work support; and a second actuating means for effecting such cutter mechanism movement in all of said units in unison.

5. Engraving mechanism comprising a pair of units disposed horizontally spaced from each other and alined and each comprising a rotary work support and a cutter mechanism movable transversely to produce relative movement between said cutter mechanism and said work support two-dimensional along the surface being engraved; a first common actuating means for effecting such work support actuation in all of said units in unison, comprising, reciprocating means operatively connected to each of said work supports and effective to rotate all of said work supports in unison upon reciprocation of said reciprocating means; and a second common actuating means for effecting such cutter mechanism movement in all of said units in unison.

6. Engraving mechanism comprising a pair of units disposed horizontally spaced from each other and alined and each comprising a work support movable in one dimension along the surface being engraved and a cutter mechanism movable in another dimension along the surface being engraved, to thus provide relative movement between said cutter and said work support two-dimensional along the surface being engraved; a first common actuating means for effecting such work support movement in all of said units in unison, comprising a co-operating means connected to each work support and by connections comprising spacing means for periodically effecting additional such movement of said work supports for the presentation, in all of said units in unison, of successive areas for engraving; and a second common actuating means for effecting such cutter mechanism movement in all of said units in unison.

7. Engraving mechanism comprising a pair of units disposed horizontally spaced from each other and alined and each comprising a rotary work support and a cutter mechanism movable transversely to produce relative movement between said cutter mechanism and said work support two-dimensional along the surface being engraved; a first common actuating means for effecting such work support actuation in all of said units in unison, comprising reciprocating means operatively connected to each of said

work supports and effective to rotate all of said work supports in unison upon reciprocation of said reciprocating means; a second common actuating means for effecting such cutter mechanism movement in all of said units in unison; and common spacing means interposed between said reciprocating means and each work support effective to periodically produce additional rotation of all of said work supports in unison to thus periodically space all of said work supports in unison for the presentation of successive areas for engraving.

8. Engraving mechanism comprising a pair of units disposed horizontally spaced from each other and alined and each comprising a work support movable in one dimension along the surface being engraved and a cutter mechanism movable in another dimension along the surface being engraved, to thus provide relative movement between said cutter and said work support two-dimensional along the surface being engraved; a first common actuating means for effecting such work support movement in all of said units in unison; and a second common actuating means for effecting such cutter mechanism movement in all of said units in unison, comprising a coordinating means connected to each said cutter mechanism.

9. Engraving mechanism comprising a pair of units disposed horizontally spaced from each other and alined and each comprising a rotary work support and a cutter mechanism movable transversely to produce relative movement between said cutter mechanism and said work support two-dimensional along the surface being engraved; a first common actuating means for effecting such work support actuation in all of said units in unison; and a second common actuating means for effecting such cutter mechanism movement in all of said units in unison, comprising coordinating means connected to each of said cutter mechanisms and effective to move all of said cutter mechanisms in unison upon movement of said coordinating means.

10. Engraving mechanism comprising a pair of units disposed horizontally spaced from each other side by side and alined and each comprising a rotary work support and a cutter mechanism movable transversely to produce relative movement between said cutter mechanism and said work support two-dimensional along the surface being engraved; a first common actuating means for effecting such work support actuation in all of said units in unison; and a second common actuating means for effecting such cutter mechanism movement in all of said units in unison, comprising a shaft connected to each of said cutter mechanisms and effective to move all of said cutter mechanisms in unison upon rotation of said shaft.

11. Engraving mechanism comprising a pair of units disposed horizontally spaced from each other and alined and each comprising a work support movable in one dimension along the surface being engraved and a cutter mechanism movable in another dimension along the surface being engraved, to thus provide relative movement between said cutter and said work support two-dimensional along the surface being engraved; a first common actuating means for effecting such work support movement in all of said units in unison, comprising a first cooperating means connected to each of said work supports; and a second common actuating means for effecting such cutter mechanism movement in all of said units in unison, comprising a second cooperating means connected to each of said cutter mechanisms.

12. Engraving mechanism comprising a pair of units disposed horizontally spaced from each other and alined and each comprising a rotary work support and a cutter mechanism movable transversely to produce relative movement between said cutter mechanism and said work support two-dimensional along the surface being engraved; a first common actuating means for effecting such work support actuation in all of said units in unison, comprising reciprocating means operatively connected to each of said work supports and effective to rotate all of said work supports in unison upon reciprocation of said reciprocating means; and a second common actuating means for effecting such cutter mechanism movement in all of said units in unison, comprising coordinating means connected to each of said cutter mechanisms and effective to move all of said cutter mechanisms in unison upon movement of said coordinating means.

13. Engraving mechanism comprising a pair of units disposed horizontally spaced from each other side by side and alined and each comprising a rotary work support and a cutter mechanism movable transversely to produce relative movement between said cutter mechanism and said work support two-dimensional along the surface being engraved; a first common actuating means for effecting such work support actuation in all of said units in unison, comprising reciprocating means operatively connected to each of said work supports and effective to rotate all of said work supports in unison upon reciprocation of said reciprocating means; and a second common actuating means for effecting such cutter mechanism movement in all of said units in unison, comprising a shaft connected to each of said cutter mechanisms and effective to move all of said cutter mechanisms in unison upon rotation of said shaft.

14. Engraving mechanism comprising a rotary cutter, cutter head means supporting said cutter for rotation and also for axial recipro-

cation to vary the depth of the cut, supporting means movably supporting said cutter head means, and means responsive to movement of said cutter head means on said supporting means for automatically varying the reciprocatory position of said cutter, comprising biasing means acting to reciprocate said cutter in one direction, and stop means for limiting such reciprocation variable automatically upon such movement of said cutter head means on said supporting means.

15. Engraving mechanism comprising a rotary cutter, cutter head means supporting said cutter for rotation and also for axial reciprocation to vary the depth of the cut, supporting means movably supporting said cutter head means, and means responsive to movement of said cutter head means on said supporting means for automatically varying the reciprocatory position of said cutter, comprising biasing means acting to reciprocate said cutter to deepen the cut, and stop means for limiting such reciprocation variable automatically upon such movement of said cutter head means on said supporting means.

16. Engraving mechanism comprising a rotary cutter, cutter head means supporting said cutter for rotation and also for axial reciprocation to vary the depth of the cut, supporting means movably supporting said cutter head means, and means responsive to movement of said cutter head means on said supporting means for automatically varying the reciprocatory position of said cutter, comprising a cam element and a follower element cooperating with said cam element, one element being fixed on said supporting means and the other element being carried by said cutter head means and movable by said one element upon such movement of said cutter head means upon said supporting means and to effect such variation in reciprocatory position of said cutter.

17. Engraving mechanism comprising a rotary cutter, cutter head means supporting said cutter for rotation and also for axial reciprocation to vary the depth of the cut, supporting means movably supporting said cutter head means, and means responsive to movement of said cutter head means on said supporting means for automatically varying the reciprocatory position of said cutter, comprising biasing means acting to reciprocate said cutter in one direction, variable stop means for limiting such reciprocation, a cam element, and a follower element cooperating with said cam element, one element being fixed on said supporting means and the other element being carried by said cutter head means and movable by said one element upon such movement of said cutter head means upon said supporting means and to vary said stop means.

18. Engraving mechanism comprising a rotary cutter, cutter head means supporting said

cutter for rotation and also for reciprocation to vary the depth of the cut, supporting means pivotally supporting said cutter head means for oscillation of said cutter head means and said cutter about such pivot, and means responsive to such oscillation of said cutter head means on said supporting means for automatically varying the reciprocating position of said cutter.

19. Engraving mechanism comprising a rotary cutter, cutter head means supporting said cutter for rotation and also for reciprocation to vary the depth of the cut, supporting means pivotally supporting said cutter head means for oscillation of said cutter head means and said cutter about such pivot, and means responsive to such oscillation of said cutter head means on said supporting means for automatically varying the reciprocating position of said cutter, comprising biasing means acting to reciprocate said cutter in one direction, and stop means for limiting such reciprocation variable automatically upon such oscillation of said cutter head means on said supporting means.

20. Engraving mechanism comprising a rotary cutter, cutter head means supporting said cutter for rotation and also for reciprocation to vary the depth of the cut, supporting means pivotally supporting said cutter head means for oscillation of said cutter head means and said cutter about such pivot, and means responsive to such oscillation of said cutter head means on said supporting means for automatically varying the reciprocating position of said cutter, comprising a cam element and a follower element cooperating with said cam element, one element being fixed on said supporting means and the other element being carried by said cutter head means and movable by said one element upon such oscillation of said cutter head means upon said supporting means and to effect such variation in reciprocating position of said cutter.

21. Engraving mechanism comprising a rotary cutter, cutter head means supporting said cutter for rotation and also for reciprocation to vary the depth of the cut, supporting means pivotally supporting said cutter head means for oscillation of said cutter head means and said cutter about such pivot, and means responsive to such oscillation of said cutter head means on said supporting means for automatically varying the reciprocatory position of said cutter, comprising biasing means acting to reciprocate said cutter in one direction, movable stop means for limiting such reciprocation, an arcuate cam element, and a follower element cooperating with said cam element, one element being fixed on said supporting means and the other element being carried by said cutter head means and movable by said one element upon such oscillation of said cutter head means upon said

supporting means and to vary said stop means.

22. Engraving mechanism comprising a plurality of units each comprising a work support, a cutter mechanism, and means supporting said work support and said cutter mechanism for rotation of said work support and oscillation of said cutter mechanism transversely, to produce relative movement between said work support and said cutter mechanism two-dimensional along the surface being engraved, and also for relative movements between said work support and said cutter mechanism in the general direction of the axis of said work support, to thus provide for adjustment for engraving surfaces of different elevation above said work supports; common actuating means for effecting said work support rotation and said cutter mechanism oscillation each in all of said units in unison; and adjusting means for effecting said axial movement in all of said units in unison.

23. Engraving mechanism comprising a plurality of units each comprising a work support, a cutter mechanism, and means supporting said work support and said cutter mechanism for rotation of said work support and oscillation of said cutter mechanism transversely, to produce relative movement between said work support and said cutter mechanism two-dimensional along the surface being engraved, and also for relative movements between said work support and said cutter mechanism in the general direction of the axis of said work support, to thus provide for adjustment for engraving surfaces of different elevation above said work supports; common actuating means for effecting said work support rotation and said cutter mechanism oscillation each in all of said units in unison; common adjusting means for effecting said axial movement in all of said units in unison; and individual adjusting means for effecting additional such axial movement in each of said units individually.

24. Engraving mechanism comprising a plurality of units each comprising a work support, a cutter mechanism, and means supporting said work support and said cutter mechanism for rotation of said work support and oscillation of said cutter mechanism transversely, to produce relative movement between said work support and said cutter mechanism two-dimensional along the surface being engraved, and also for movement of said cutter mechanism and said work support both in the general direction of the axis of said work support, to thus provide for adjustment for engraving surfaces of different elevation above said work supports; common actuating means for effecting said work support rotation and said cutter mechanism oscillation each in all of said units in

unison; common adjusting means for effecting said axial movement in all of said cutter mechanisms in unison; and individual adjusting means for effecting such axial movement of said work supports in each of said units independently. 70

25. Engraving mechanism comprising a plurality of units each comprising a work support, a cutter mechanism, and means supporting said work support and said cutter mechanism for rotation of said work support and oscillation of said cutter mechanism transversely, to produce relative movement between said work support and said cutter mechanism two-dimensional along the surface being engraved, and also for relative movements between said work support and said cutter mechanism in the general direction of that radius of said work support extending through the cutting point, to thus provide for adjustment for engraving surfaces of different radius; common actuating means for effecting said work support rotation and said cutter mechanism oscillation each in all of said units in unison; and adjusting means for effecting said radial movement in all of said units in unison. 80 90

26. Engraving mechanism comprising a plurality of units each comprising a work support, a cutter mechanism, and means supporting said work support and said cutter mechanism for rotation of said work support and oscillation of said cutter mechanism transversely, to produce relative movement between said work support and said cutter mechanism two-dimensional along the surface being engraved, and also for relative movements between said work support and said cutter mechanism one axial in the general direction of the axis of said work support and the other radial in the general direction of that radius of said work support extending through the cutting point, to thus provide for adjustment for engraving surfaces of different elevation above said work supports 100 and of different radius; common actuating means for effecting said work support rotation and said cutter mechanism oscillation each in all of said units in unison; and adjusting means for effecting said axial movement and said radial movement each in all of said units in unison. 110 115

27. Engraving mechanism comprising a plurality of units each comprising a work support, a cutter mechanism, and means supporting said work support and said cutter mechanism for rotation of said work support and oscillation of said cutter mechanism transversely, to produce relative movement between said work support and said cutter mechanism two-dimensional along the surface being engraved, and also for relative movements between said work support and said cutter mechanism one axial in the general direction of the axis of said work sup- 120 125 130

port and the other radial in the general direction of that radius of said work support extending through the cutting point, to thus provide for adjustment for engraving surfaces of different elevation above said work supports and of different radius; common actuating means for effecting said work support rotation and said cutter mechanism oscillation each in all of said units in unison; 5 common adjusting means for effecting said axial movement and said radial movement each in all of said units in unison; and individual adjusting means for effecting additional such axial movement in each of said 10 units independently.

28. Engraving mechanism comprising a plurality of units each comprising a work support, a cutter mechanism, and means supporting said work support and said cutter 20 mechanism for rotation of said work support and oscillation of said cutter mechanism transversely, to produce relative movement between said work support and said cutter mechanism two-dimensional along the surface being engraved, and also for relative 25 movements between said work support and said cutter mechanism one axial in the general direction of the axis of said work support and the other radial in the general direction of that radius of said work support 30 extending through the cutting point, to thus provide for adjustment for engraving surfaces of different elevation above said work supports and of different radius; common 35 actuating means for effecting said work support rotation and said cutter mechanism oscillation each in all of said units in unison; a first adjusting means for effecting said axial movement in all of said units in unison; 40 and a second adjusting means for effecting said radial movement in all of said units in unison.

In testimony whereof I hereunto affix my signature.
